MATERIAL GATHERING AND LOADING
MACHINE

Frank Cartlidge, Chicago, Ill., assignor to Goodman Manufacturing Company, Chicago, Ill., a corporation of Illinois

Application March 29, 1941, Serial No. 385,819

9 Claims. (Cl. 198—8)

This invention relates to improvements in material gathering and loading machines adapted to load coal at the working face of a mine.

The principal objects of the invention are to provide a simple and efficient low machine of the character described, suitable for operation in thin seams of coal and arranged with a view towards increased accessibility to the parts of the machine and compactness and simplicity in construction, together with increased flexibility in manipulation and control, with a resultant increased loading capacity over former machines of this type.

Other objects of the invention will appear from time to time as the following specification proceeds and with reference to the accompanying drawings wherein:

Figure 1 is a top plan view of the front part of a loading machine constructed in accordance with my invention;

Figures 2 and 3 are enlarged views in side elevation of the loading machine, with certain parts broken away and with certain other parts shown in longitudinal section;

Figure 4 is an enlarged plan view of the central part of the machine, with certain parts broken away and certain other parts shown in horizontal section;

Figure 5 is an enlarged partial fragmentary longitudinal sectional view taken through the central part of the conveyer in order to show certain details of the conveyer and the drive therefor;

Figure 6 is an enlarged detail plan view of the forward part of the machine, with certain parts broken away and with certain other parts shown in horizontal section in order to illustrate certain details of the tensioning means for the conveyer;

Figure 7 is an enlarged partial fragmentary detail plan view of the forward part of the machine, with certain parts shown in horizontal section in order to illustrate certain details of the drive to the gathering mechanism;

Figure 8 is an enlarged partial fragmentary plan view of the central part of the machine, with certain parts broken away and certain parts shown in horizontal section in order to more clearly illustrate certain details of the drive to the gathering mechanism;

Figure 9 is a partial fragmentary plan view somewhat similar to Figure 8, but with certain other parts removed and shown in section and with the support for the gathering mechanism shown in one extreme position of adjustment;

Figure 10 is an enlarged detail view illustrating

certain details of the bearing support for a part of the drive means to the gathering mechanism;

Figure 11 is a transverse sectional view taken substantially along line 11—11 of Figure 4;

Figure 12 is a transverse sectional view taken substantially along line 12—12 of Figure 4;

Figure 13 is a view in side elevation of the forward part of the machine, illustrating certain details of the elevating mechanism for the gathering mechanism;

Figure 14 is a longitudinal sectional view taken through the elevating cylinder;

Figure 15 is a view somewhat similar to Figure 14, with the piston shown in a different position than in Figure 14; and

Figure 16 is a longitudinal sectional view taken substantially along line 16—16 of Figure 8.

Like reference characters refer to like parts throughout the several figures.

20 Referring now to the details of the machine as shown in the drawings, the main elements thereof consist of a wheeled truck or main frame 10, an inclined gathering element 11 disposed in advance of said main frame, and a conveyer 12 extending from a point adjacent the ground, in advance of said main frame, and over the top of said main frame, beyond the rear end thereof in an overhanging position, so as to discharge material into mine cars or the like. Said conveyer is herein shown as being of the single center strand endless chain and flight type, and the material moving elements thereof include an endless chain 13 having spaced apart flights 14, 14, secured thereto and projecting laterally therefrom in opposite directions.

30 The main operating parts of the machine are driven from a motor 15, supported at the rear end of the main frame 10 between side frame members 16, 16 thereof. Said motor has power connections for driving the truck wheels, for driving the gathering mechanism 11 and conveyer 12, and for driving a suitable pump 17, for building up fluid pressure for laterally swinging and raising or lowering the gathering element 40 and for laterally swinging and raising or lowering the discharge end of the conveyer 12.

45 The endless conveyer chain 13 of the conveyer 12 is of a well known laterally flexible gibbed type, pivotally movable about vertical as well as horizontal axes, and is adapted to ride in guides extending along the conveyer in a manner which will hereinafter more clearly appear as this specification proceeds. Said endless chain is driven from a transverse shaft 30, by means of a chain and sprocket drive 70 (see Figures 3, 4 and 5),

The shaft 30 is driven from the motor 15 by means a bevel pinion 21 journaled on its hub in a bearing 22, mounted in an end wall of a gear casing 23. Said bevel pinion is driven from the splined rear end portion of a longitudinal shaft 27, which is coaxial with the motor shaft, and is driven therefrom through a flexible coupling 28. Said bevel pinion meshes with a pair of opposed bevel gears 29, 29 on aligned transversely extending shafts 30 and 31 for driving said shafts in reverse directions. Friction clutches 34 and 41 are mounted on said shafts and form a means for selectively driving the loading machine therefrom in reverse directions without reversal of the motor 15. The drive connections from said shafts to the track wheels for the loading machine will not herein be described in detail since they form no part of my present invention.

The chain and sprocket drive 10 has driving connection with a transverse shaft 71 through a friction slip clutch 72, herein shown as being of the friction cone type (see Figure 12). A spur gear 73 is freely mounted on said shaft, adjacent the end thereof opposite from the chain and sprocket drive 10, and is selectively driven therefrom by means of a jaw clutch 74. Said spur gear meshes with a spur gear 75 on a transverse shaft 76, for driving said shaft (see Figures 4 and 5). A sprocket 77 is keyed on said shaft and meshes with and drives the conveyer chain 13.

The endless conveyer chain 13 extends over an idler roller 78 on the transverse shaft 71, under the drive sprocket 77, over an idler roller 79 spaced forwardly of said sprocket, and into and along a downwardly opening gibbed guide 80a on the forward end of an intermediate stationary trough section 80, of the conveyer. From thence it passes through gibbed guides 81, 81 on the undersides of articulated connecting trough segments 82, 82, through a gibbed guide 83 on the underside of a trough section 84, mounted on the forward end of a laterally swingable frame 107, which forms a support for an inclined portion 85 of the conveyer. Said inclined portion of the conveyer extends forwardly from the forward end of said swingable frame, to the ground. From said trough section said chain extends downwardly beneath the inclined portion 85 of the conveyer, to and around an idler roller 86 at the forward end of said inclined portion. From thence said chain extends upwardly along a bottom plate 87 of said inclined portion of the conveyer, in a gibbed guide 87a and through a gibbed guide 88 on the upper side of a slidable trough section 84a, nested within the trough section 84. From said guide said chain extends through gibbed guides 89, 89 on the upper sides of the trough segments 82, 82, through a gibbed guide 90 on the upper side of the intermediate trough section 80 of the conveyer, and through gibbed guides 91, 91 on the upper side of articulated connecting trough segments 92, 92, and beyond said segments to the rear end of the conveyer, around a suitable idler (not shown), and forwardly along the bottom of the discharge end of the conveyer, to and over the idler roller 78, under the drive sprocket 77 and over the idler roller 78.

During the passage of the endless chain 13 downwardly along the underside of the inclined portion 85 of the conveyer, it passes over an idler roller 97, under a tension roller 99, and over an idler roller 100 on a transverse shaft 101 (see Figures 2 and 6). Said tension roller is mounted on a transverse shaft 102, which is mounted at its ends on lever arms 103, 103 of bell cranks

104, 104. Said bell cranks are coaxially mounted in opposite side frame members 105, 105 of the inclined portion 85 of the conveyer. Said transverse shaft 101 is mounted coaxially with the axis of pivotal movement of said bell cranks. The other lever arms of said bell cranks are disposed outside of said side frame members and project upwardly and have tension springs 106, 106 connected thereto, for positively engaging the roller 99 with said endless chain, and for maintaining said chain taut in all positions of articulation of the conveyer.

The inclined portion 85 of the conveyer is transversely pivoted at its rear end on the upper forward end of the swinging frame 107. Said swinging frame is pivotally mounted at the forward end of the main frame 10, for movement about a vertical axis, and projects forwardly from said main frame a substantial distance to form an outboard support for said inclined portion of said conveyer (see Figures 3 and 4).

The transverse pivotal mounting for said inclined portion of the conveyer includes recessed bosses 108a, 108a, projecting laterally from opposite side frame members 105, 105 (see Figure 4) and adapted to be engaged by inwardly extending bosses 109, 109, projecting inwardly from support brackets 109, 109. Said support brackets are secured to opposite sides of and project forwardly from the upper forward end of the swinging frame 107.

The laterally swinging frame 107 includes a lower portion 107a, which is provided with a depending boss 110 journaled in a bearing member 111 at the forward end of the main frame 10, and mounted in a cross frame member 111a (see Figures 3 and 11). Said swinging frame also includes an upper portion 107b, spaced upwardly from said lower portion and provided with an upwardly projecting boss 112, journaled in a bearing member 113 mounted in a cross frame member 114 of said main frame. Said upper portion of said swinging frame is provided with a rearwardly projecting portion having an arcuate engaging face 115, which is adapted to be engaged by a flexible chain 116, for laterally swinging said frame about the axes of the bosses 110 and 112 (see Figures 3, 4, 8 and 9).

The means for swinging said frame includes a longitudinally extending cylinder 117, mounted on the left hand side plate 16 and having a pair of vertically spaced piston rods 118, 118, extensible therefrom. The chain 116 is connected between said piston rods, intermediate its ends, by a connecting member 118a thereof, in a manner clearly shown and described in my prior application Serial No. 308,565, filed Nov. 15, 1940, now Patent No. 2,239,978, and no part of my present invention so not herein shown or described in detail. Said chain extends forwardly from its point of connection to said piston rods, around a guide sheave 119, and angularly inwardly therefrom towards the rear of the machine, to and around a sheave 120. From thence it extends towards the left hand side of the machine, around the arcuate face 115, and is yieldably connected to the left hand end of said arcuate portion by means of a connecting bolt and spring 121 (see Figure 8). Said chain also extends in a rearward direction from its point of connection to the piston rod 118, around a guide sheave 122, and inwardly and angularly forwardly therefrom towards the right hand side of the machine, and is connected at its end to the right hand end of the arcuate engaging face 115 by means of a connecting bolt and

spring 123. Thus when fluid under pressure is admitted to one end or the other of said cylinder, said piston rods will swing said elevating conveyer laterally, in an obvious manner.

The means for elevating the gathering mechanism and inclined elevating portion of the conveyer about the axis of the bosses 108, 108 includes a pair of laterally spaced fluid pressure cylinders 126, 126, slidably supported in cylindrical supporting members 127, 127 which are pivotally connected to opposite sides of the swinging frame 107 (see Figures 2, 8, 13, 14 and 15). Each of said cylinders and supporting members is of a similar construction so the construction of one only will herein be described in detail. As herein shown, the cylindrical support member 127 is provided with a pair of spaced apart rearwardly projecting ears 127, 127, extending along opposite sides of and pivotally connected with a lug 129, projecting forwardly from the swinging frame 107, adjacent the lower outer end thereof (see Figures 8 and 13). A compression spring 130 is mounted within said cylindrical support member and is interposed between the inside of said support and the outside of a head end 131 of said cylinder, to form a cushioning means for the inclined conveyer and loading element (see Figures 14 and 15). A bolt 132 extends through a boss 133 of said cylindrical support member and is threaded within a boss 134, projecting rearwardly from the head end of the cylinder 126, to limit outward movement of said cylinder with respect to said cylindrical support member and to adjust the extent of movement of said cylinder with respect to said support member.

A piston 135 is mounted within each cylinder 126. Each of said cylinders has a piston rod 136 projecting therefrom. Said piston rods are pivotally connected at their outer ends with brackets 137, 137, depending from opposite sides of the inclined elevating portion of the conveyer intermediate the ends thereof. Thus, when fluid under pressure is admitted to the head end of the cylinders 126, 126, the gathering mechanism and forward end of the elevating conveyer will be elevated above the ground about the axis of pivotal connection of said forward end to the bearing bosses 108, 108, and when fluid pressure is released from the head ends of said cylinders, said gathering and loading element will move in a downward direction against the compression springs 130, 130. Said cylinders may also be used to raise the front track wheels off the ground, to aid in re-railing the machine when it is off the track, by the admission of fluid under pressure to the piston rod ends of said cylinders. This will move the gathering and loading element in a downward direction towards the ground and will positively engage the forward end of said gathering and loading element with the ground. Further movement of said gathering and loading element in a downward direction will jackknife said gathering and loading element about the axes of bosses 108, 108, which will lift the front end of the machine about the rear track wheels. During such operation, engagement of the boss 133 with the boss 134 will form a stop to limit depression of the forward end of the gathering and loading element, and when pressure is relieved from the piston rod ends of said cylinders, the compression springs 130, 130 will tend to elevate the forward end of said gathering and loading element to a normal position.

The gathering element 11 is herein shown as being of a construction somewhat similar to that

illustrated in my prior Patent No. 2,135,882, so will not herein be described in detail, and includes an inclined plate 225 extending along opposite sides of the conveyer and across the forward end thereof. A pair of chain guiding members 226, 226 having endless chains 227, 227 guided for orbital movement thereabout, are mounted on the upper side of said plate and extend along opposite sides of and forwardly of said conveyer. Spaced gathering arms 228, 228 project laterally from said chains, for picking up material from the ground and moving it along the front end of said apron onto said conveyer (see Figures 1 and 2).

Each gathering chain 227 is driven from a sprocket 230, mounted on the upper end of a shaft 231, journaled for rotation about an axis perpendicular to the plane of inclination of the plate 225. A spur gear 233 is keyed on said shaft, adjacent the lower end thereof, and meshes with and is driven from a spur pinion 234 on a shaft 235. A bevel gear 236 on the lower end of said shaft serves to drive said shaft and is driven from a bevel pinion 237 on the forward end of a longitudinally extending shaft 238. Said shaft is journaled in a gear housing 239, which forms a bearing support for the shafts 231 and 235, and a housing for the gears 233, 234, 236 and 237. A universal coupling 240 is connected to the rear end of said shaft, and has connection with a universal coupling 241 at the rear end of the inclined elevating portion of the conveyer by means of a rearwardly projecting splined shaft 242, which slidably engages a forwardly projecting internally splined sleeve 243, connected at its rear end with the universal coupling 241. Said last mentioned universal coupling is connected to and driven from a longitudinally extending shaft 244, journaled in the swinging frame 107, in suitable bearing support members 245, 245. A sprocket 246 is mounted on said shaft between the bearing support members 245, 245, and serves to drive said shaft (see Figures 8 and 11). The right hand drive sprocket 246 is driven from a sprocket 247, journaled on a longitudinal shaft 249, by means of drive chains 250, 250. The left hand sprocket 246 is driven from a parallel sprocket 251 by means of drive chains 252, 252 (see Figures 8 and 11). The sprockets 247 and 251 are connected together by means of a pair of spur gears 253, 253, mounted on the hubs of said respective sprockets.

The drive sprocket 251 is journaled on its hub in the swinging frame 107 on ball bearings 254, 254 and is selectively driven from a coaxial longitudinal shaft 255 by means of an over-load release clutch 255, herein shown as being of a friction slip type of disk clutch (see Figures 3, 8 and 16).

The friction clutch 255, as shown in Figure 16, includes a helical gear 260 mounted on the forward end of the shaft 255. Said helical gear engages with internal helical teeth formed within the inner periphery of a driving member 261. Driving and driven friction disks 264, 264 are interposed between said driving member and a driven member 265. Said driven member is keyed to the hub of the sprocket 251. A compression spring 266 engages an engaging member 267 with the end disk 264, and holds said disks in driving connection with each other. Said compression spring engages the inner side of an adjustable spring housing 268 at its end opposite from said engaging member. Said housing is threaded

within a forwardly projecting portion 289 of the driven member 265, for adjustment.

Upon overload of the gathering mechanism, the driving member 281 will move outwardly along the teeth of the helical gear 260 and move the engaging member 267 against the compression spring 266, to permit disengagement of the clutch.

The clutch 256 is positively disengaged by means of a fluid cylinder 270 having a piston rod 271 extensible therefrom (see Figure 8). Said piston rod has pivotal connection with an arm of a clutch yoke 276. Said clutch yoke is pivoted intermediate its ends and engages a clutch collar 277 on the end of a clutch rod 278, slidably mounted in the housing 268, and extending outwardly therefrom. An enlarged inner portion 279, of a semi-spherical formation, is provided on the inner end of said rod and engages the inner side of the engaging member 267, to positively release said clutch, upon the admission of fluid under pressure to said cylinder. Fluid under pressure is supplied to said cylinder by the pump 17, through suitable piping (not shown).

The shaft 265 is driven from the motor 13 through the forward end of the shaft 27. Said shaft extends longitudinally forward of the bevel pinion 21, through the casing 23 and beyond the forward end thereof (see Figures 3 and 8). The forward end of said shaft 27 extends within an internally splined sleeve 280, journaled within a bearing member 281 mounted at the forward end of the casing 23. A flanged forward end of the splined sleeve 280 is connected with a flanged yoke 282 of a universal coupling 283, by means of nuts and bolts 284, 284. Said flanged yoke is pivotally connected with a cross 285 of said coupling, for universal pivotal movement with respect thereto about a pair of perpendicular axes, and the opposite end of said cross is universally pivotally connected to a yoke 286, for pivotal movement about a pair of perpendicular axes. Said last mentioned yoke is herein shown as having an internally splined sleeve 287 projecting forwardly therefrom, which is journaled in a laterally swinging bearing support member 288 on ball bearings 290, 290 (see Figures 3, 8 and 9). Said bearing support member is pivotally connected adjacent its rear end with the main frame 10 by means of a pivotal pin 291 (see Figure 3). Said bearing support member extends forwardly and over the lower portion of said laterally swinging frame and is provided with a longitudinally extending slot 292, open towards its forward end, which has engagement with the head of a pin 293 projecting upwardly from the lower portion of said frame.

A splined shaft 294 is slidably mounted within the internally splined sleeve 287, and is herein shown as being formed integral with a yoke 295 of a universal coupling 296, similar to the coupling 283. Said universal coupling is provided with another yoke 297 connected to the cross thereof, and having a splined shaft 299 projecting forwardly therefrom and slidably engaging a splined sleeve 300, journaled in a bearing support member 301, on ball bearings 302, 302. Said splined sleeve has driving engagement with the splined rear end of the shaft 255, for driving said shaft.

It may be seen from the foregoing that the bearing support member 289 moves in a controlled path, upon laterally swinging movement of the swinging frame 101, and holds the splined

sleeve 281 in such a position as to split the angles between the universal joints 283 and 296, to reduce the angularity of the yokes of the two joints with respect to each other, so the drive sprockets 246 and 247 may be driven through said universal couplings upon all positions of lateral swinging movement of said gathering mechanism with respect to the truck 10. This arrangement permits the gathering mechanism to be efficiently driven when swung 50 degrees to each side of the longitudinal center line of the machine and forms a simple and efficient form of direct drive, taking up a minimum amount of vertical height and eliminating the usual bevel gear train necessary to drive a laterally movable gathering mechanism from a stationary motor.

20 While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a loading device of the class described, a track mounted truck including a main frame, a motor mounted on said main frame, a swinging frame projecting forwardly from the forward end of said main frame and mounted on said main frame for lateral swinging movement about a vertical axis, a conveyer mounted on said swinging frame and extending forwardly therefrom to the ground in an inclined direction, gathering elements extending along opposite sides of the forward end of said conveyer, for picking up loose material from the ground and moving it onto said conveyer, and drive connections from said motor to said gathering elements including a longitudinally extending shaft mounted on said swinging frame, adjacent the forward end thereof, a bearing support member pivotally mounted on said main frame, adjacent the forward end thereof, a controlling connection between the forward end of said bearing support member and said swinging frame, for pivotally moving said bearing support member in a controlled path, upon swinging movement of said swinging frame, a drive member journaled in said bearing support member, a universal coupling connecting said motor with said drive member, and another universal coupling connecting said drive member with said longitudinally extending shaft.

2. In a loading device of the class described, a track mounted truck including a main frame, a motor mounted on said main frame, a swinging frame mounted on and projecting forwardly from the forward end of said main frame, said swinging frame being laterally movable about a vertical axis, a conveyer mounted on said swinging frame and extending forwardly therefrom to the ground in an inclined direction, gathering elements extending along opposite sides of the forward end of said conveyer, for picking up loose material from the ground and moving it onto said conveyer, and drive connections from said motor to said gathering elements including a longitudinally extending shaft mounted on said swinging frame, adjacent the forward end thereof, a drive member mounted on said main frame, for transverse swinging movement with respect thereto, a universal coupling connecting said motor with said drive member, another universal coupling connecting said drive member with said longitudinally extending shaft.

dinal shaft, and a transversely movable bearing support member for said drive member, adapted to support said drive member in such a manner as to move said drive member across the axis of swinging movement of said swinging frame, upon movement of said frame from one extreme position to another, and said bearing support member having pivotal connection with said main frame and overlapping said swinging frame.

3. In a loading device of the class described, a track mounted truck including a main frame, a motor mounted on said main frame, a swinging frame mounted on said main frame adjacent the forward end thereof and projecting forwardly from the forward end of said main frame, said swinging frame being laterally movable about a vertical axis, a conveyer mounted on said swinging frame and extending forwardly therefrom to the ground in an inclined direction, gathering elements extending along opposite sides of the forward end of said conveyer, for picking up loose material from the ground and moving it onto said conveyer, and drive connections from said motor to said gathering elements including a longitudinally extending shaft journaled in said swinging frame, adjacent the forward end thereof, a drive member mounted on said main frame, for transverse swinging movement with respect thereto, a universal coupling connecting said motor with said drive member, another universal coupling connecting said drive member with said longitudinal shaft, and a transversely movable bearing support member for said drive member, said bearing support member having pivotal connection with said main frame and overlapping said swinging frame, and a guiding connection between said swinging frame and said bearing support member to cause said bearing support member to move said drive member across the axis of swinging movement of said swinging frame, upon movement of said frame from one extreme position to another.

4. In a loading device of the class described, a track mounted truck including a main frame, a motor mounted on said main frame, a swinging frame mounted on said main frame adjacent the forward end thereof and projecting forwardly from the forward end of said main frame, said swinging frame being laterally movable about a vertical axis, a conveyer mounted on said swinging frame and extending forwardly therefrom to the ground in an inclined direction, gathering elements extending along opposite sides of the forward end of said conveyer, for picking up loose material from the ground and moving it onto said conveyer, and drive connections from said motor to said gathering elements including a longitudinally extending shaft journaled in said swinging frame, adjacent the forward end thereof, a drive member mounted on said main frame, for transverse swinging movement with respect thereto, a universal coupling connecting said motor with said drive member, another universal coupling connecting said drive member with said longitudinal shaft, and a transversely movable bearing support member for said drive member, said bearing support member having pivotal connection with said main frame and overlapping said swinging frame, and a guiding connection between said swinging frame and said bearing support member including a pin on one of said members engageable with a slot on said other member, for moving said bearing support member and drive member across the axis of swinging movement of said swinging frame, upon

movement of said frame from one extreme position to another.

5. A loading machine of the class described having in combination a track mounted main frame, a motor on said main frame, a swinging frame projecting forwardly from the forward end of said main frame and mounted on said main frame for lateral swinging movement about a vertical axis, an inclined conveyer mounted on said swinging frame and extending forwardly therefrom to the ground, gathering elements extending along opposite sides of the forward end of said inclined conveyer, for picking up loose material from the ground and moving it onto said conveyer, and drive connections from said motor to said gathering elements including a longitudinally extending shaft mounted on said swinging frame, adjacent the forward end thereof, a pair of drive sprockets mounted for rotation about laterally spaced longitudinal axes on the upper portion of said swinging frame, adjacent opposite sides thereof, flexible geared drive connections extending along opposite sides of said conveyer for driving said gathering elements from said sprockets, and chain and sprocket drives from said longitudinal shaft to said sprockets.

6. A loading machine of the class described having in combination a track mounted main frame, a motor on said main frame, a swinging frame projecting forwardly from the forward end of said main frame and mounted on said main frame for lateral swinging movement about a vertical axis, an inclined conveyer mounted on said swinging frame and extending forwardly therefrom to the ground, gathering elements extending along opposite sides of the forward end of said inclined conveyer, for picking up loose material from the ground and moving it onto said conveyer, and drive connections from said motor to said gathering elements including a longitudinally extending shaft mounted on said swinging frame, adjacent the forward end thereof, another shaft parallel to said shaft and driven therefrom, two laterally spaced drive sprockets mounted on said swinging frame adjacent the upper end thereof for rotation about parallel longitudinal axes, flexible geared drive connections extending along opposite sides of said conveyer, for driving said gathering elements from said sprockets, and individual chain and sprocket drives from said longitudinal shafts to said sprockets.

7. A loading machine of the class described having in combination a track mounted main frame, a motor on said main frame, a swinging frame projecting forwardly from the forward end of said main frame and mounted on said main frame for lateral swinging movement about a vertical axis, an inclined conveyer mounted on said swinging frame and extending forwardly therefrom to the ground, gathering elements extending along opposite sides of the forward end of said inclined conveyer, for picking up loose material from the ground and moving it onto said conveyer, and drive connections from said motor to said gathering elements including a longitudinally extending shaft mounted on said swinging frame, adjacent the forward end thereof, another shaft parallel to said shaft and driven therefrom, two laterally spaced drive sprockets mounted on said swinging frame adjacent the upper end thereof for rotation about parallel longitudinal axes, flexible geared drive connections extending along opposite sides of

said conveyer, for driving said gathering elements from said sprockets, individual chain and sprocket drives from said longitudinal shafts to said sprockets, and two spaced interconnected universal couplings connecting said motor with said first mentioned longitudinal shaft and arranged to drive said longitudinal shaft from said motor in all positions of said swinging frame and inclined conveyer with respect to said motor.

8. A loading machine of the class described having in combination a track mounted main frame, a motor on said main frame, a swinging frame projecting forwardly from the forward end of said main frame and mounted on said main frame for lateral swinging movement about a vertical axis, an inclined conveyer mounted on said swinging frame and extending forwardly therefrom to the ground, gathering elements extending along opposite sides of the forward end of said inclined conveyer, for picking up loose material from the ground and moving it onto said conveyer, and drive connections from said motor to said gathering elements including a longitudinally extending shaft mounted on said swinging frame, adjacent the forward end thereof, another shaft parallel to said shaft and driven therefrom, two laterally spaced drive sprockets mounted on said swinging frame adjacent the upper end thereof for rotation about parallel longitudinal axes, flexible geared drive connections extending along opposite sides of said conveyer, for driving said gathering elements from said sprockets, individual chain and sprocket drives from said longitudinal shafts to said sprockets, a drive member mounted on said main frame, for transverse swinging movement with

respect thereto, a universal coupling connecting said motor with said drive member, another universal coupling connecting said drive member with said first mentioned longitudinal shaft, 5 and a transversely movable bearing support for said drive member, said bearing support being pivotally mounted on said main frame and overlapping a lower portion of said swinging frame, and having guiding connection with said swinging frame whereby said swinging frame will move said bearing support and drive member in a controlled path, upon swinging movement of said frame.

9. In a loading machine of the class described having in combination a track mounted truck, an inclined elevating conveyer projecting forwardly from the forward end of said truck, gathering mechanism extending along opposite sides of said conveyer, adjacent the forward end thereof, and a supporting connection for said elevating conveyer on said truck including a swinging frame journaled on said truck for movement about a vertical axis and projecting forwardly therefrom, a shaft extending longitudinally of said frame, adjacent the lower end thereof, said frame having a forward vertically extending widened portion disposed in advance of said truck and having said conveyer journaled thereon for transverse pivotal movement with respect thereto, and a pair of sprockets driven from said shaft and journaled in opposite sides of said widened portion, for rotation about longitudinal axes, and disposed beneath the conveyer and forming a drive means for said gathering mechanism.

FRANK CARTLIDGE.
